MAGNIFYING ATTACHMENT FOR BOOKS

Gertrude J. Pierce, Alfred, Maine

Application March 5, 1948, Serial No. 13,191

1 Claim. (Cl. 88—39)

1

My present invention relates to an improved magnifying attachment for books and generally comprises a magnifying lens mounted in a suitable frame to which is attached at one end thereof a spring clamp for securing the frame to a page of a book or magazine or other printed or written matter so that it may be easily slid from top to bottom of the page or sheet as the matter is read.

In the accompanying drawings I have illustrated one complete example of the physical embodiment of my invention according to the best mode I have thus far devised, but it will be understood that various changes and alterations may be made in the exemplified structure within the scope of the appended claim.

In the drawings:

Fig. 1 is a top plan view of the attachment of my invention.

Fig. 2 is a side elevational view.

Fig. 3 is a sectional view at line 3—3 of Fig. 2.

Fig. 4 is a sectional view at line 4—4 of Fig. 1.

Referring now to the drawings wherein I have illustrated the present preferred embodiment of my invention, I employ an elongated magnifying lens of plastic preferably but which may be made of glass if desired, having a convex upper face 2 and plane lower face 4, with tapered ends 6 and 8.

This lens, generally of rectangular shape, is secured in the angular groove 10 of the frame 12 and the lower face of the lens is spaced from the under surface of the frame so that the lens will be spaced from the reading matter.

At one end of the frame, in the slot 14 I secure the fixed jaw of the clamp section 16 of angular shape and the cylindrical and resilient tube 18 split at 20 is mounted by means of slots 22—24 on this section. In slots 26—28, is secured the opposing clamp section or jaw 30 of angular shape and having an extension 32 extending under the end section of the frame.

It will be apparent that by compressing together the clamp sections, the extension 32 will be spaced from the frame against the tension of the tube, and the frame and lens may be located

on the paper or sheet 34 of book 36 and the extension under the sheet will clamp the sheet between the extension and the frame.

Thus the lens will be releasably retained in the selected position and may be easily moved along the edge of the sheet by releasing the clamp sections.

Having thus fully described my invention, what I claim as new and desire to secure by Letters

10 Patent is:

In a magnifying reading attachment, the combination which comprises a flat frame having an angular groove in the inner peripheral edge, a magnifying lens mounted in said frame with the edge thereof conforming to and positioned in the said groove so that the face of the lens extends beyond the face of the frame, and a spring clamp having a pair of gripping jaws with outwardly extended handles and a spring for urging the said 15 gripping jaws together, one of said jaws fixedly attached to said flat frame at one end thereof and the other of said jaws positioned to engage the bottom surface of the edge of the frame to which the first jaw is fixed to temporarily secure 20 the said frame on an edge of a sheet of material whereby the frame positions the magnifying lens against the surface of the said sheet of material to enlarge indicia thereon.

GERTRUDE J. PIERCE.
